(57) **CLAIM**

The ornamental design for a portable electronic device, as shown and described.

DESCRIPTION

It will be appreciated that a “portable electronic device” includes any portable electronic device, such as portable computer, notebook computer, personal digital assistant, tablet personal computer, laptop computer, and the like.

FIG. 1 is a top view of a portable electronic device with the display panel open;

FIG. 2 is a bottom view of the portable electronic device of FIG. 1 with the display panel open;

FIG. 3 is a front view of the portable electronic device of FIG. 1 with the display panel closed and the screen facing up;

FIG. 4 is a left side view of the portable electronic device of FIG. 1 with the display panel closed and the screen facing up;

FIG. 5 is a right side view of the portable electronic device of FIG. 1 with the display panel closed and the screen facing up;

FIG. 6 is a rear view of the portable electronic device of FIG. 1 with the display panel closed and the screen facing up;

FIG. 7 is a perspective view of the portable electronic device of FIG. 1 with the display panel open; and,

FIG. 8 is a top view of the portable electronic device of FIG. 1 with the display panel in closed and the screen facing up.
